COMPRESSED AIR ELECTRIC ARC CUTTING AND GOUGING TORCH COMBINATION

Harold R. Henderson, Stephen A. Hoffman, and Myron D. Stepath, Lancaster, Ohio, assignors to Arcair Company, Lancaster, Ohio

Filed Sept. 16, 1969, Ser. No. 19,173

Term of patent 14 years

Int. Cl. D8—02

U.S. Cl. D8—98

FIG. 1.

FIG. 2.

FIG. 3.

FIG. 4.

FIG. 1 is a perspective view from the left side of the new compressed air electric arc cutting and gouging torch combination.

FIG. 2 is a perspective view taken of the right side of the new design.

FIG. 3 is a top plan view of the new design.

FIG. 4 is a side elevation view of the new design.

We claim:

The ornamental design for a compressed air electric arc cutting and gouging torch combination, substantially as shown.
